LOCK CONSTRUCTION

Emil J. Heineman, Chicago, Ill., assignor, by
mesne assignments, to Keil Lock Co. Inc.,
Charlestown, N. H., a corporation of New
Hampshire

Application February 2, 1945, Serial No. 575,748

3 Claims. (Cl. 292—169)

1

This invention relates to lock construction.

One of the objects of this invention is to provide a practical and inexpensive lock construction constructed and operating so that the bolt, upon being withdrawn by a suitable control member—such as a part operated by a key—can be held withdrawn against the action of the bolt spring so that the hand of the operator working the key may be free, in turn to operate the door knob or latch lever, as when the person has an armful of packages or the like. Another object is to provide a simple, practical, and inexpensive means for converting known types of lock construction, such as a night latch, so that the bolt may be held against projection, but still under the control of the key. Another object is, in general, to provide an improved night latch mechanism, and other objects will be obvious or in part pointed out hereinafter.

The invention, accordingly, consists in the features of construction, combinations of elements, and arrangements of parts as will be exemplified in the structure to be hereinafter described and the scope of the application of which will be indicated in the following claims.

In the accompanying drawings, in which is shown an illustrative embodiment of my invention,

Fig. 1 is a longitudinal central sectional view through the assembled lock mechanism;

Fig. 2 is an elevation as seen along the line 2—2 of Fig. 1; and

Fig. 3 is a detached end elevation of one form of cam as seen from the left in Fig. 2, other parts being omitted.

Similar reference characters refer to similar parts throughout the several views of the drawings.

Referring, first, to Fig. 1, I provide a lock casing 10 having a top wall 11, front and back end walls 12 and 13, respectively, and opposed side walls 14 and 15, the casing being adapted to be closed by a back plate 16 which is preferably in the form of a stamping of suitable heavy sheet metal and which is positioned in spaced relation from the front wall 11 by suitable lugs 18 in the internal side and end walls of the casing 11 and also by a substantially centrally positioned post 19 that projects from and is integrally formed with the front wall 11.

Projectile from a suitable opening in the end wall 12 is a bolt 20, illustratively shown as being a latch bolt, and it is extended inwardly of the casing with various parts of which, including the back plate 16, it coacts to be guided in its movement into or out of locking relation with respect to a suitable keeper (not shown).

Illustratively bolt 20 may be bifurcated, having two parallel arms that extend toward the right, terminating in vertical lugs 23 and 24 adapted

2

to be engaged by the cam 25 that is to be operated internally of the door, as by a knob 26, rotatably mounted in the front wall 11, and by a cam 27 that is to be operated by the connecting bar 28 attached to the key-controlled key plug 29 rotatably mounted in a suitable bore of the lock cylinder or barrel 30, of any usual or suitable type key-controlled tumbler mechanism.

The bolt 20, where it is of the latch type, has a spring 32 to bias it outwardly of the casing 10, one end of the spring extending over a suitable tapered lug 33, projecting to the right from the head of the bolt and the other end of the spring abutting against the post 19, the spring 32 being accommodated amply in the space between the arms 21 and 22 of the bolt 20; any suitable means may be employed to limit outward projection of the bolt 20, and, conveniently, that may be done by a cross-piece or cross-bar 34 that extends from one arm 21 to the other 22, being conveniently cast integrally therewith and being positioned so that it engages the post 19 at just the point where outward projection of the bolt 20 is to be limited. Suitable lugs projecting upwardly and downwardly, as seen in Fig. 1, from the bolt structure and including the end lugs 23 and 24, engage the top wall 11 and the back plate 16, or engage suitable guideways in the front wall 11, so that the bolt 20 is slideably guided for movement in withdrawal or projecting directions.

In accordance with certain features of my invention I provide, instead of a simple hole in the back plate 16—for the passage therethrough of the securing screw 36 that is threaded into the post 19—a slot 37 of suitable width to pass therethrough the shank of the screw 36 and of appropriate length in the direction toward the cam 27 that effects withdrawal of the bolt 20. I then provide a sheet-metal part, generally indicated by the reference character 38, and preferably made of spring steel, and shape it to have a flat base portion 39 that is of greater expanse (Fig. 2) than the slot 37 in the back plate 16 when its right-hand edge is in substantial alignment with the right-hand end wall of the slot 37. At its right-hand end the part 38 has an extension 40 bent upwardly from the base 39, and the part 40 is substantially V-shaped in horizontal cross-section and extends at an angle to the vertical, inclining away from the cam 27, and, if desired, it may have some curvature in the vertical plane, as indicated in Fig. 1.

The base portion 39 has in it a hole 39^a so that when the base 39 is made to overlie the underside of the back plate 16, the shank of the screw 36 may be passed through the hole 39^a, and so that the screw 36 not only holds the back plate 16 in position, but also holds part 38 in assembled relation, its base portion 39 being clamped by the screw against the under face of the back

plate. The lateral dimension or width of the V-shaped inclined part 40 is, particularly at its lower end, dimensioned to substantially snugly fit the width of the slot 37, so that the part 38 is aligned along the central longitudinal axis (Fig. 2) and cannot partake of rotary movement about the axis of the screw 36. Being made of spring metal, the inclined part 40 may thus be given some yieldability or springiness, and, under stress, it may, therefore, yield in counter-clockwise direction, as seen in Fig. 1, flexing substantially about its junction to the base portion 39, while some downward yieldability or springiness may also accompany such resiliency of part 40, due to some springiness in the base portion 39 itself, that part of which to the right of the screw 36 being capable of some springy action.

The just-described parts of the device 38 and its location are related to the cam 27, which is rotatably mounted in the back plate 16 and which is constructed to have a cam edge of varying height above the back plate 16 for coaction with the inclined resilient part 40. The cam 27 may, therefore, have a flat, plate-like, central portion 27^a which can rest against the upper face of back plate 16, and extending therefrom the cam 27 has arms 27^b and 27^c which, as seen in Fig. 3, lie in a plane above the plane of the central portion 27^a, being joined thereto by inclined portions 27^d and 27^e. The left-hand edge of the center portion 27^a and the left-hand edges of the portions 27^b, 27^d, 27^e, and 27^c may fall in the arc of a circle whose center coincides with the axis of the bearing portion or portions of the cam 27 itself; the cam 27 is rotatably carried by the back plate 16, but preferably in a manner to provide looseness of fit therebetween, and, hence, radial play, which may be on the order of $\frac{1}{32}$ of an inch or so, and any suitable rotary mounting of the cam in the back plate may be employed.

Preferably, however, I employ a mounting of the kind shown and described in U. S. Patent No. 2,225,545, to which reference may be made for greater details of construction and action, and for present purposes it will suffice to point out that I first provide in the back plate 16 a circular hole 41 provided with a cutout or extension 41^a that extends to the right, and then I provide the center portion 27^a of the cam 27 with two arcuate portions 27^d and 27^e that are of a radius of curvature sufficiently less than the radius of the hole 41 to provide play, as above noted. The ends of the parts 27^d and 27^e are extended or bent over into parallelism with the center portion 27^a, forming retaining lips 27^b and 27^c which are dimensioned to be of lesser radial and peripheral extent than the extension 41^a of the hole 41.

Accordingly, a bearing portion 27^e and its lip 27^c may be snaked through the hole 41, cam 27 rotated to bring the opposite lip 27^b into alignment with the hole extension 41^a, through which it is then passed to bring it to the other side of the plane of plate 16, whence continued rotary movement brings it underneath the plate 16 so that it, together with the companion and opposite lip 27^b, can now hold the cam 27 against disassembly, while permitting substantial or adequate rotation thereof relative to the plate 16.

In the arms 27^b and 27^c are cut notches 27^m and 27ⁿ shaped appropriately to coact with the V-shaped member 40. With both arms 27^b and 27^c engaging the lugs 23 and 24 of the bolt, the front edge of the cam just about contacts the part 40, and, as soon as the cam is given a re-

tary movement, in either direction—as by turning connecting bar 28 by means of the key plug controlled by the key 42—one of the cam arms moves toward the right and starts the bolt 20 moving also to the right, increasing the compression of spring 32, with the result that the joint action of the spring and of the torque imposed upon the cam 27 causes the play in the rotary mounting of the cam to be taken up on that side of the bearing surface of the hole 41 that is generally to the left, as viewed in Figs. 1 and 2. During this rotary movement of cam 27, an upwardly inclined portion of the cam, either part 27^d or part 27^e, has its front edge brought into engagement with the part 40, but, due to the upward inclination of that front edge, the latter coacts with progressively higher portions of the exposed edge of part 40, the latter being inclined toward the left, as shown in Figs. 1 and 2, and these coacting cam parts may be related—as by appropriately setting or adjusting the inclination or curvature of the part 40 with or without predetermination of the rate of inclination of the part 27^d or the part 27^e (Fig. 3)—so that the above-mentioned shift of the play in the bearing of cam 27 is not materially affected or is partially taken up by causing some shift of the cam 27 generally to the right, and particularly in the latter case the parts are being prepared for ensuing coaction with the part 40 of a notch in the cam. Continued rotary movement brings the notched edge of the arm 27^b or 27^c into coaction with an upper portion of the part 40, the notch finally engaging the part 40, and, under the force of the compressed spring 32, the notch snaps into engagement with the part 40 to shift, or to complete the shift, of the play in the bearing of cam 27, so that full interengagement between the cam notch and the part 40 results. The bolt is thus held in retracted position.

With the cam 27 thus held by the part 40, the connecting bar 28, which extends through a suitable hole 27^t in the cam 27, is likewise held in rotated position, as are also the key plug or barrel 29 and the key 42, these positions of the parts 29-30 preventing the withdrawal of the key; to release the bolt 20, the key 42 is given a slight torque to start it turning in reverse direction, and, when only a slight turn is given it, the notch of the cam snaps out of engagement with the part 40, aided by the play in the cam mounting, whence the energy stored in the spring 32 snaps the bolt into projected position and returns the cam 27 to its normal position—which is all shown in Figs. 1 and 2.

It will be noted that the actions above described can take place without calling into play any spring action or springiness of the part 40 or its mounting, and in such case the desired coactions are achievable due to the intentional looseness of fit or play in the cam mounting so as to permit bodily shift of the cam. Where it might be undesirable to have such looseness or play, principal reliance may be placed upon a spring action given to the part 40, and, in the illustrative embodiment, as above noted, this spring action is achieved by the springiness of the metal at the junction between the part 40 and the base 39, and this may be supplemented by a flexing of the part 39 itself, permitting the part 40 to yield toward or away from the fixed axis of the cam 27. With such an arrangement, the front edges of the parts 27^d, 27^e, and 27^t, as seen in Fig. 3, need not contact the spring part 40 at all throughout the range of rotary movement of the cam 27, or, as is pre-

ferred, the parts 27^d and 27^e, with their upwardly-inclined front edges, can engage the part 40 and against its resiliency cam it to the left, so that, when either the notch 27^m or notch 27^p is next brought into coaction with the part 40, the latter can snap back—that is, toward the right and into the notch—and thus releasably hold the cam 27 against further rotary movement. During this camming action by either part 27^d or part 27^e, smoothness and ease of forcing the spring part 40 to the left are achieved by the upwardly inclined edge of the cam coacting with the inclined front edge of the part 40, thus progressively increasing the leverage of the cam upon the part 40 to force the latter toward the left, and thus avoiding imposing undue load upon the parts being operated by the turning of the key 42.

The parts are thus all held in retracted or withdrawn positions, and, to restore them to the positions shown in Figs. 1 and 2, the key 42 is manually strained in the direction of reverse rotation, thus bringing into action upon the part 40 the above-mentioned greater leverage, for the cam part (notch 27^m or 27^p) that has its edge coacting with the part 40 at this stage is an elevated part (see Fig. 3) and thus engages the uppermost portion of the part 40 to exert maximum leverage thereon. The part 40 thus yields and is strained again to the left, and, at the moment that the cam notch and part 40 are disengaged, the energy stored in the compressed spring 32 immediately snaps the bolt and cam and key plug and key back to normal position.

Both of the above-described actions—that is, looseness or play in the rotary mounting of the cam and resiliency of action in the part 40—may be conjointly employed, and, in such case, a lesser amount of play in the rotary mounting of the cam and a lesser amount of resiliency of the compression of the part 38 may be employed, and part 38 may thus be made of heavier spring stock than if entire reliance were to be placed upon its resiliency. In utilizing both of these actions, the spring action which the device 38 is called upon to contribute is of smaller magnitude, smaller ranges of flexing of the spring parts can take place, and thus a longer-lasting construction results, in that spring fatigue is less likely to occur.

The construction will be seen to be inexpensive and easily applicable to a known or suitable form of latch construction; for example, the part 38 is of simple fabrication and is easily mounted in position, use being made of the back plate mounting screw 36 and of a change of shape of aperture (slot 37) in the back plate which would have to be pierced anyway to accommodate the screw 36. A standard cam, as in the above-mentioned patent, can be employed and need simply be notched, so long as its front edges coact appropriately with the part 40, and where looseness of rotary mounting of the cam is desired, one need only stamp or pierce a hole 41 of suitably larger radius of curvature.

Thus it will be seen that there has been provided in this invention a lock construction in which the various objects above set forth, together with many thoroughly practical advantages, are successfully achieved.

As many possible embodiments may be made of the above invention and as many changes might be made in the embodiment above set

forth, it is to be understood that all matter hereinbefore set forth or shown in the accompanying drawing is to be interpreted as illustrative and not in a limiting sense.

5 I claim:

1. A lock construction comprising a casing having a wall in the form of a back plate, the back plate having a hole to receive a screw and the casing having a threaded hole, a spring-biased bolt projectible into or out of the casing, a cam member loosely journaled in the back plate having operating connections with the bolt for actuating the bolt, and operatively connected to a key operated connector bar, a device made of sheet metal and having a base portion resting against the external face of said back plate and having an operating portion projecting through the hole in the back plate having an inclined bearing surface directed away from said cam, a screw threaded into the threaded casing hole for holding the back plate and said device assembled to the casing, said operating portion of said device and said cam having interengageable parts for releasably holding said cam member and bolt against movement and comprising a notched portion on the cam engaging a projection on said operating portion aforesaid.

2. A lock construction as claimed in claim 1, in which said operating portion of said device is resiliently yieldable relative to its base portion to thereby effect yieldable interengagement between said parts.

3. In a lock construction having a casing and a spring biased projected latch bolt, a key controlled plug and a connecting bar rotated thereby adjacent one end, said bar having its other end extending into a bolt retractor cam in keying engagement and with radial play, a bearing formed in a back plate of said casing for said cam, said bearing being in axial alignment with said latch bolt and said cam being trunnioned in said bearing with radial play, said cam having peripheral edges formed with detent portions at points of substantially full retraction of the latch bolt by the cam and engaging a cooperating fixed portion which, under the radial play of the cam, holds the latch bolt in the retracted position, the bar and cam also responding to the spring biased action of the latch bolt independently of the rotative action of the key controlled plug to cause engagement of the said detent and fixed portions.
